UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE

TYPEWRITING MACHINE.

Application filed December 29, 1923. Serial No. 683,267.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

This invention relates to continuous billing typewriting machines, and more particularly to means in machines of this class for controlling the field of the platen to which the multiple-ply work-web and the interleaved carbons will be fed. In certain 15 of its novel aspects, the invention is not limited to continuous billing machines, however.

The continuous billing machine usually includes a carbon-carrier movable along a 20 carriage-extension toward and from the platen. A multiple-ply continuous work-web is introduced into the machine at the rear and is led forward through the carbon-carrier to be interleaved with the carbons 25 thereof. The web with the interleaved carbons passes forward around the revoluble platen, which is displaced to permit straightening of the web and carbons so that the carbons may be withdrawn from the forms 30 of a typed web-section and interleaved with the next succeeding section by pushing the carbon-carrier to the rear. The carbon-carrier is mounted to travel toward and from the platen upon the rear carriage-extension, 35 and is arranged to partake with the latter of the letter-feed and return movements of the carriage.

In some classes of work it is desirable to use a comparatively wide record-sheet 40 with a narrow bill-web. It may be desirable, in accordance with the nature of the work, to superpose the bill-web upon the right portion, the left portion, or an intermediate portion of the record-sheet. In 45 still other cases it may be desirable to arrange the bill-web and the record-sheet in partially overlapping relation so that each has a margin extending clear of the other, or in non-overlapping relation so that they 50 pass side by side around the platen.

It is a feature of the present invention that the bill-web may be caused to occupy any relation to the record-sheet that may be desired in a particular case. To this end, 55 the carriage-extension, which supports and

guides the carbon-carrier in its travel toward and from the platen, and which includes front and rear side guides for the bill-web, is adjustably connected to the carriage so that it may be arranged in line 60 with various fields of the platen and may be connected for travel with the carriage when so arranged. The carriage-extension is connected to travel with the carriage in letter-feed and return directions by means 65 of a transverse bar having notches at intervals along it, at either one or both ends, the bar being mounted on the carriage, and forwardly-extending hooks or brackets on the carriage-extension arranged to engage 70 in selected notches of the bar to connect the carriage-extension in the desired relation longitudinally of the platen, the connection with the bar also preferably preventing unintentional vertical dislodgment of either 75 end of the carriage-extension. In this manner, the right and left side guides for the bill-web at both the front and rear of the carriage-extension, together with the carbon-carrier, are adjusted at a single operation 80 to direct the bill-web and the interleaved carbons to the field of the platen desired.

Other features and advantages will hereinafter appear. 85

In the accompanying drawings,

Figure 1 is a sectional side elevation of a part of a continuous billing machine having the present improvements applied thereto. 90

Figure 2 is a plan view of a portion of the machine.

Figure 3 is a diagrammatic view showing the bill-web superposed upon the right portion of the record-sheet. 95

Figure 4 is a view, similar to Figure 3, showing the bill-web superposed upon the left portion of the record-sheet.

In the continuous billing machine, which may be of the type disclosed in the patent 100 to Wernery & Smith, No. 1,132,055, granted March 16, 1915, types 10 swing upwardly and rearwardly to strike against the front of a revoluble platen 11, journaled by its axle 12 in a swing-frame 13 mounted in a 105 traveling carriage 14, that is supported and guided for movement in letter-feed and return directions upon a front rail (not shown) and a rear rail 15 on the machine-frame 16. A multiple-ply bill-web 17 is in 110

roduced into the machine over a rear bar 18 of a carriage-extension 19. This carriage-extension 19 is supported at its rear by means of rollers 20 (one of which is shown) 5 that run upon a rail 21 at the rear of an extension 22 of the machine-frame 16, and includes rails 23 on which a carbon-carrier 24 is reciprocable toward and from the platen 11. The bill-web 17 is interleaved 10 with carbons 25 carried by blades 26 of the carbon carrier 24, and passes forward with them around the platen 11 and upward over a front paper-table 27 forming part of the swing-frame 13. At line-spacing, the 15 carbon-carrier 24 advances with the bill-web 17 toward the platen 11, and, when a bill has been completely typed, the swing-frame 13 is rotated about its axis 28 to raise the platen and thus permit straightening 20 of the web 17 so that it may be drawn forward to a gage 29 and the carbons 25 may be retracted by thrusting the carbon-carrier 24 to the rear.

For the purpose of providing a composite 25 record of the bills, a record-sheet 30 is passed around the platen 11 in back of the bill-web 17 in position to receive impressions from the innermost carbon carried by the carbon-carrier 24. At the delivery side 30 of the platen 11, the record-sheet 30 passes to the rear of the front paper-table 27 so that it is not drawn forward to the gage 29 with the bill-web 17, but remains stationary during this operation. Neither is it torn 35 off with the bill-web 17 when the latter is drawn against the knife 31 after gaging. A clamp, comprising a jaw 32, may be provided to clamp the record-sheet 30 stationary against the back of the front paper-table 27 40 while the platen 11 is displaced. This clamp may be like the one disclosed in the application of Jesse A. B. Smith, Serial No. 558,139, filed May 3, 1922 (now Patent No. 1,543,731, dated June 30, 1925).

45 Provision is made of means for guiding the relatively narrow bill-web 17 and its interleaved carbons 25 to any field of the platen desired, so that the bill-web 17 will overlap the desired portion of the record-sheet 30, in accordance with the needs of the particular work. As shown in Figure 3, for example, the bill-web 17 is positioned with its right side edge substantially flush with the right side edge of the record-sheet 50 30. In Figure 4, the bill-web 17 is shown with its left side edge substantially flush with the left side edge of the record-sheet 30. These views are simply illustrative of 55 a great number of ways in which the bill-web and the record-sheet may be relatively positioned by means of the present invention.

60 For the purpose of enabling the bill-web guiding means to be thus adjusted relatively to the platen, the carriage-extension 19 is

detachably connected to the carriage 14 of the machine, and provision is made of means for securing the extension 19 to the carriage in any one of a large number of positions transversely of the machine, that is, in 65 alignment with various fields of the platen 11. At its forward end, the carriage-extension 19 is provided with forwardly-projecting hooks or brackets 33, having downwardly-opening slots 34 at their forward 70 ends, arranged to embrace a transverse bar 35 carried by brackets 36 that extend rearwardly from the carriage 14 adjacent opposite ends thereof. The bar 35 has sets of notches 37 formed at intervals to provide 75 reduced portions with which the slotted portions 34 of at least one of the brackets 33 may interfit. The sets of notches are in this instance arranged in pairs, the sets of a pair being spaced from each other to correspond to the spacing of the brackets 33, but a single set would suffice. Upon the right-hand bracket 33 there is secured a 80 stiff spring 38 having a hook 39 at its lower end to snap beneath the bar 35 and detain 85 the bracket or hook 33 in place thereon, so that the carriage-extension 19 will be connected to the carriage securely and yet in a yielding manner so as to permit its ready removal. The opposite end is equipped with 90 a similar spring 38 or other equivalent means to prevent rising from the bar.

95 A rod 40 extends between the brackets 33 at the front of the carriage-extension 19, and upon this rod 40 are mounted right and 100 left side guides 41 for the bill-web 17, which may be adjusted to correspond to the width of the web 17. Right and left side guides 42 for the bill-web 17 are also mounted on the bar 18 at the rear of the carriage-extension 19, and these side guides 42 co-operate 105 with the side guides 41 to direct the bill-web 17 through the carbon-carrier 24 and to the desired field of the platen 11. Since the front side guides 41, the rear side guides 42 110 and the carbon-carrier 24 are all mounted on the carriage-extension 19, it will be seen that all of these parts may be adjusted at a single operation and without disturbing their co-operative relation to each other 115 by removing the brackets or hooks 33 from engagement with the bar 35 and securing them in a new position to the bar 35.

120 The leading-edge gage 29 for the bill-web 17 is mounted on a gage-bar 43 that is held in place on the front paper-table 27 by a knurled screw 44 threaded in to an opening 45 in the table 27. In order to enable the gage 29 to co-operate properly with the bill-web in various adjusted positions of the carriage-extension, several openings 45 are provided in the paper-table, into which the screw 44 may be threaded. The upper end 46 of the paper-table 27 is turned back and is provided with cutaways 47, the side walls 125

of which engage and steady the gage-bar 43. There is one of these cutaways 47 corresponding to each of the screw-receiving openings 45 in the table.

5 Variations may be resorted to within the scope of the invention, and portions of the improvements may be used without others.

Having thus described my invention, I claim:

10 1. In a typewriting composite web machine, a traveling carriage, a revolute platen journaled therein, a carbon-carrier reciprocable toward and from the platen, web-plies threaded through said carbon-carrier, and means for adjusting the carbon-carrier to locate the carbons and webs in line with various fields of the platen.

20 2. In a typewriting machine, a traveling carriage, a revolute platen journaled therein, a carbon-carrier reciprocable toward and from the platen, a track on which the carbon-carrier travels in its movement toward and from the platen, and means for adjusting the track to guide the carbon-carrier to different selected fields of the platen.

30 3. In a typewriting machine, in combination, a traveling carriage, a displaceable, revolute platen therein, a rear carriage-extension arranged to travel with the carriage, a carbon-carrier reciprocable toward and from the platen, the carbon-carrier being supported and guided on the carriage-extension, side guides for the work on the carriage-extension, to the front and rear of the carbon-carrier, to guide the work through the carbon-carrier and to the desired field of the platen and to prevent misplacement of the work when the platen is displaced, and means for adjusting the carriage-extension longitudinally of the platen to change at a single operation the position of the side guides and of the carbon-carrier to direct the work and the carbons to a different field of the platen.

40 4. In a typewriting machine, in combination, a traveling carriage, a displaceable, revolute platen therein, a rear carriage-extension arranged to travel with the carriage, a carbon-carrier reciprocable toward and from the platen, the carbon-carrier being supported and guided on the carriage-extension, side guides for the work on the carriage-extension, to the front and rear of the carbon-carrier, to guide the work through the carbon carrier and to the desired field of the platen and to prevent misplacement of the work when the platen is displaced, means on the carriage-extension to detachably connect it to the carriage, and means on the carriage to co-operate with said connecting means to secure the carriage-extension to the carriage in alignment with different fields of the platen.

45 5. In a typewriting machine, in combina-

tion, a traveling carriage, a displaceable, revolute platen therein, a rear carriage-extension arranged to travel with the carriage, a carbon-carrier reciprocable toward and from the platen, the carbon-carrier being supported and guided on the carriage-extension, side guides for the work on the carriage-extension, to the front and rear of the carbon-carrier, to guide the work through the carbon-carrier and to the desired field of the platen and to prevent misplacement of the work when the platen is displaced, means on the carriage-extension to detachably connect it to the carriage, and means on the carriage to mechanically select positions of attachment for the carriage-extension to align it with different selected fields of the platen.

6. In a typewriting machine, in combination, a traveling carriage, a revolute platen therein, a rear carriage-extension having a carbon-holder and work-guiding means upon it, and means detachably connecting the carriage-extension to the carriage, comprising interengaging members and a spring to yieldingly hold said members in engagement with each other.

7. In a typewriting machine, in combination, a traveling carriage, a revolute platen therein, a rear carriage-extension having a carbon-holder and work-guiding means upon it, and a snap fastening device detachably connecting the carriage-extension to the carriage.

8. In a typewriting machine, a traveling carriage, a revolute platen therein, a carriage-extension bearing a carbon-holder and work-guiding means, a notched bar on the carriage, hooks on the carriage-extension to interfit with the notched portions of the bar, the walls of the notches detaining the carriage-extension in fixed relation to the carriage, and there being enough notches provided to afford a variety of adjusted positions for the carriage-extension relatively to the carriage, and means for yieldingly detaining the hooks in interfitting relation with the bar.

9. In a typewriting machine, a traveling carriage, a revolute, displaceable platen therein, a rear carriage-extension having work-guides and a carbon-holder mounted upon it, the carriage-extension being adjustable to direct the work-web and carbon to different selected fields of the platen, a leading-edge gage at the delivery side of the platen to which the work-web may be drawn when the platen is displaced, and means for securing the leading-edge gage in a variety of positions longitudinally of the platen in accordance with the adjustment of the rear carriage-extension.

10. A typewriting machine for typing a succession of bills upon a continuous bill-web and at the same time making a com-

posite record of the bills on a record-sheet passed between the bill-web and the platen, having, in combination, a traveling carriage, a revoluble, displaceable platen 5 therein, a rear carriage-extension having bill-web guides and a carbon-holder mounted upon it, the carriage-extension being adjustable to direct the bill-web and carbons to different selected fields of the platen, and a clamp for holding the record-sheet stationary while the platen is displaced; the arrangement being such that the bill-web and record-sheet may be relatively positioned longitudinally of the plat-

en by adjustment of the carriage-extension 15 and will be thereafter retained in the same relation longitudinally of the platen throughout the writing of the bills.

11. In a typewriting machine, the combination of a platen around which work-sheets may be fed, a table over which the work-sheets may be conducted to the platen, means to enable said table to be adjusted to various fields lengthwise of the platen, and 20 a leading-edge gage for the work-sheets adjustable lengthwise of the platen to the various fields. 25

JOHN WALDHEIM.
